PERFORATING DISK

Filed Dec. 15, 1927

Fig. 2.

INVENTOR
George A. Colman
BY
G. Wright Arnold
ATTORNEY

UNITED STATES PATENT OFFICE.

GEORGE A. COLMAN, OF SEATTLE, WASHINGTON.

PERFORATING DISK.

Application filed December 15, 1927. Serial No. 240,140.

My invention relates to an improved perforator disk of a perforating machine.

More particularly, my invention relates to a timber perforating disk used in conjunction with a timber perforating mechanism such as is disclosed in my co-pending application, Serial No. 608,242.

In perforating poles for use in telegraph poles or piling for purposes of more thoroughly impregnating said poles with a preserving compound, great difficulty is experienced in providing clean-cut perforations. That is, difficulty is experienced with the present type of perforating disk where the perforating pins are rigidly held in the disk because of the tendency to tear or splinter the pole.

A primary purpose of my invention is to overcome these objections, and to provide a perforator which is simple in construction, and does not break or dull the perforating pin points to the objectionable degree which is at present experienced with the usual form of perforating disk.

The above mentioned general objects of my invention, together with others inherent in the same, are attained by the mechanism illustrated in the following drawings, the same being a preferred exemplary form of embodiment of my invention, throughout which drawings like reference numerals indicate like parts:

Figure 1 is a view in side elevation of a disk embodying my invention with parts broken away, showing the pins in operative engagement with a pole; and

Fig. 2 is a view on dotted line 2, 2 of Fig. 1.

A perforating disk housing 3 is preferably provided with a flange 4 in which are pin receiving recesses 5 which recesses have an inner pin guide opening 6 and an outer pin guide opening 7, the latter being preferably provided in a bushing 8'. In said openings a perforating pin 8 is located which may have a collar 9 operatively disposed to strike against shoulder 10. A resilient means which may be in the form of a spring 11 bears against collar 9 and bushing 8', tending to hold collar 9 against shoulder 10 thereby retracting the pin 8 within recess 5.

Disk housing 3 is rotatively mounted on shaft 12. Axle 13 is mounted on bracket 14.

Idly mounted on axle 13 is a pin depressing roller 15 preferably so mounted by means of roller or ball bearings 16. Said depressing roller 15 is of less diameter than the inner periphery of flange 4, and is of such diameter as to cause the outer periphery of said roller 15 to extend nearly to the inner periphery of flange 4 in order that it may forcibly engage the retracted pins 8.

The mode of operation of a device embodying my invention in addition to that described above is as follows:

As the pole 18 is caused to revolve against disk housing 3 the said housing is rotated and the perforating pins 8 are one by one brought beneath the roller 15 which successively gradually force outwardly or depress said pins to a predetermined extent required to make the perforation of the desired depth. Manifestly, the pins are gradually caused to pierce the pole as said pins rotate towards the diametrical alignment 17-17 and are gradually permitted to retract as they move beyond said alignment. This avoids tearing the edge of the perforations which often occurs when the pins are rigidly held in the perforating disk, since no provision is made for adjusting the length of the protruding pin in respect to the diametrical alignment of the pin and disk with respect to the pole.

This mode of operation avoids breaking the pins or dulling the same and provides a most efficient perforating disk in practical operation.

By providing the outer guide opening 7 in a bushing 8 a simple means is provided for assembling the pin 8 and the spring 11 within the recess 5 and also a ready means is provided for replacing said pins when it is desired to sharpen the points of said pins.

Obviously, changes may be made in the form, dimensions and arrangement of the parts of my invention, without departing from the principle thereof, the above setting forth only a preferred form of embodiment.

I claim:

A pile perforating disk embodying a housing idly mounted having a peripherally disposed flange with perforating pin mounting recesses therein, said recesses having an inner and outer pin guiding opening the outermost of which openings is formed in a bushing;

perforating pins slidably mounted therein, said pins having a collar formed thereon which limits the inner displacement of said pin; resilient means bearing against the collar of said pin and said bushing, said means normally holding said pins retracted in said recesses; an axle; a mounting bracket for said

axle; and a pin depressing roller idly mounted on said axle whereby said roller may depress said pins successively when said housing is caused to rotate by means of a rotating pile. 10

In witness whereof I hereunto subscribe my name this 7th day of December, 1927.

GEORGE A. COLMAN.
